United States Patent Office.

ISAAC A. SHEPPARD, OF PHILADELPHIA, PENNSYLVANIA.

Design No. 2,790, dated September 24, 1867.

DESIGN FOR A STOVE-PLATE.

The Schedule referred to in these Letters Patent and making part of the same.

ALL WHOM IT MAY CONCERN:

Be it known that I, ISAAC A. SHEPPARD, of Philadelphia, county of Philadelphia, State of Pennsylvania, invented or produced a new and original Design for the Panel of a Stove-Plate or Door; and I do hereby declare that the accompanying drawing, and the following explanation thereof, form a full, clear, and exact description of the said design.

In the accompanying drawing the figure represents the panel of a stove-plate or door, which is bordered by plain edging, *a*. In the centre of the panel is a diamond-shaped figure, *b*, which is bordered by an ornamental piping, *e*, and across which extends a belt, *d*. On the face of the panel surrounding the figure *b* are the ornamental foliated and scroll-like figures shown in the drawing.

I claim the design for the panel of a stove-plate or door, substantially as shown in and by the accompanying drawing.

In testimony whereof I have signed my name to this specification in the presence of two subscribing witnesses.

ISAAC A. SHEPPARD.

Witnesses:

CHARLES HOWSON,

C. E. FOSTER.
